Primary Examiner — Susan Bennett Hattan*Assistant Examiner* — Rebecca Tsehay(74) *Attorney, Agent, or Firm* — Scully, Scott, Murphy & Presser, P.C.(57) **CLAIM**

The ornamental design for plate lids, as shown and described.

DESCRIPTION

FIG. 1 is a perspective view of the plate lids showing our new and ornamental design;

FIG. 2 is a top view thereof;

FIG. 3 is a side view thereof;

FIG. 4 is an alternate side view thereof; and,

FIG. 5 is a bottom view thereof.

The portions of the plate lids shown in broken lines shown in the figures attached hereto form no part of the claimed design.
